FIXED DIFFERENTIAL ADJUSTING MEANS
FOR PRESSURE SENSITIVE ELECTRICAL
CONTROL DEVICESWilliam E. Brown, Pewaukee, Wis., assignor to
Cutler-Hammer, Inc., Milwaukee, Wis., a corporation of Delaware

Application November 25, 1949, Serial No. 129,468

8 Claims. (Cl. 200—83)

1

This invention relates to pressure sensitive electrical control devices and more particularly to a fixed differential adjusting means therefor.

As is well known, control devices of the aforementioned character are designed to open an electrical circuit at a predetermined pressure (or temperature) and to reclose the circuit at a different predetermined pressure (or temperature), the difference between the aforementioned pressures (or temperatures) being the "differential" of the control device.

In the known arts of manufacturing pressure sensitive electrical control devices, the cumulation of manufacturing tolerances in the electrical control assemblies renders it impractical to obtain a predetermined fixed operating differential by means of close adherence to actual contact spacing, contact pressure, and confined arc gap. Hence the desired operating differential is usually obtained by fixing the arc gap to an approximate dimension and setting the differential by varying the wear allowance, or fixing the wear allowance and setting the differential by varying the arc gap. This necessitates pneumatic or thermostatic equipment for setting the differential. Moreover the differential is secured without providing for simultaneous control of both the amount of wear allowance and the size of the arc gap.

A primary objective of the present invention is to eliminate the aforementioned undesirable characteristics of prior devices of the type under consideration, and more particularly to provide in pressure (or temperature) responsive electrical control devices means affording accurate and simultaneous predetermination of contact arc gap, wear allowance, and differential.

Another object is to achieve the aforementioned simultaneous predetermination of all three factors through the medium of a single adjusting member, which member may be extremely accurately and yet inexpensively and practically produced.

Another object is to provide in a control device of the aforementioned character means for varying the ratio of contact arc gap to contact wear allowance without changing the sum of those two factors and hence without affecting the differential of the device, thus permitting reestablishment of a desired contact wear allowance when the contacts have worn down without affecting the differential of the device.

Another object is to provide means of the aforementioned character affording accurate simultaneous predetermination of differential, con-

2

tact wear allowance and arc gap without the necessity of either visual or other access to the interior of the contact operating mechanism to check the accuracy of contact travel and arc gap, thus permitting utilization of wholly enclosed electrical contact mechanisms.

Other objects and advantages of the invention will hereinafter appear.

The accompanying drawings illustrate an embodiment of the invention which will now be described, it being understood that various modifications may be made in the embodiment illustrated without departing from the spirit and scope of the appended claims.

15. In the drawings,

Figure 1 is a somewhat schematic view of a control device embodying the invention, and

Fig. 2 is a side elevation of a fixed differential screw utilized in the control device.

20. Referring first to Fig. 1, the reference numeral 5 denotes a pair of spaced stationary contacts within a circuit (not shown) to be controlled, which contacts 5 are adapted to be bridged by a contactor 6 biased to the closed position by a spring 7.

To effect movement of contactor 6 out of bridging engagement with contacts 5 a snap acting system comprising pivoted levers or flippers 8 and 9, and an over-center spring 10 connected therebetween is provided. Movement of said snap acting mechanism is in turn controlled by a conventional pressure (or temperature) responsive means shown as comprising a bellows assembly 11, loading spring 12, and range adjusting means 13 comprising a screw 13^a and a non-rotatable nut 13^b. As will be apparent, increased pressure in the bellows 11 will effect upward movement of the outer end of the flipper 9 connected thereto until spring 10 goes through center, thus effecting snap movement of lever 8 to the dotted line position shown in Fig. 1, thus providing for corresponding movement of contactor 6 into bridging engagement with contacts 5, through the medium of spring 7.

45. As previously pointed out, one of the objects of the present invention is the provision of means for effecting an accurately predetermined fixed differential in electrical control devices of the character described. In the embodiment illustrated, the aforementioned means takes the form of a fixed differential screw 14 which, as shown in Fig. 2, has a peripheral groove 14^a formed therein, by machining or otherwise, to provide spaced parallel surfaces 14^b and 14^c.

50. Screw 14 is adapted for threading into the

mounting plate 15 of the control device in such relation to the aforementioned snap acting mechanism as to permit the free end of flipper 8 to oscillate upwardly and downwardly within the limited space afforded by groove 14^a of screw 14. As best illustrated in Fig. 2, the spacing of surfaces 14^b and 14^c affording the limits to travel of the free end of lever 8 is calculated to equal the desired contact wear allowance and arc gap plus the thickness of lever 8, such spacing being accurately and inexpensively provided in screw 14, as by machining or otherwise, and with tolerances of .001 inch or less.

For example, if it were desired to have .032 inch wear allowance, .025 inch arc gap, and the thickness of lever 8 were .030 inch, it would be necessary to machine or otherwise form groove 14^a to .087 inch.

In assembling the control the threaded portion 14^d of fixed differential screw 14 may be threaded into mounting plate 15 until lever 8 is forced to just open the contacts. Screw 14 is then backed off enough to provide the desired predetermined wear allowance, for example, for a #8-32 screw thread, one full turn would give a desired wear allowance of .032 inch. Screw 14 may then be retained in this position by conventional retaining means, such as a non-rotatably supported frictional spring wire clip 16. Since the total travel of lever 8 is limited by groove 14^a to an exact maximum adjusting the control for a predetermined wear allowance provides a definite arc gap and simultaneously an accurately controlled and uniformly close predetermined differential for each control device produced.

Moreover, the aforescribed desired relationship of screw 14 and flipper 8 having once been established, an enclosing casing of conventional form (not shown) affording no access to screw 14, visual or otherwise, may be assembled to the control since no further adjustment is necessary, the control having already been set with a known predetermined fixed differential and accurately predetermined contact wear allowance and arc gap. Thus utilization of pneumatic or thermostatic means is not necessary to effect initial setting of the control device, nor are further adjustments necessary to achieve such initial setting.

However, at such time as the contacts have worn down to a point where the predetermined wear allowance has been dissipated, the screw 14 may be readjusted to reestablish the desired contact wear allowance without changing the differential of the device, since the parallel surfaces limiting travel of lever 8 will be moved simultaneously in the same direction and to the same degree, their relationship being fixed.

I. claim:

1. A pressure responsive electrical control device comprising a set of contacts, a pressure responsive operating element therefor, and means affording simultaneously a predetermined fixed operating differential for said device and a contact arc gap and wear allowance the ratio of which may be varied while the sum thereof remains constant, said means affording adjustability to reestablish a contact wear allowance to compensate for contact wear without affecting said operating differential and comprising integrally formed fixedly spaced surfaces to limit travel of said operating element, and the spacing of said surfaces being equal to the sum of the desired wear allowance and arc gap of said contacts plus the thickness of said operating element.

2. A pressure responsive electrical control de-

vice comprising a set of electrical contacts, a pressure responsive operating element therefor, and means affording simultaneously a predetermined fixed operating differential for said device and a predetermined total contact arc gap and wear allowance, said means affording adjustability to reestablish a contact wear allowance to compensate for contact wear without affecting said operating differential and comprising a screw having a peripheral groove of predetermined width forming a pair of integrally formed fixedly spaced parallel surfaces between which said operating element is adapted to oscillate, said surfaces limiting the travel of said operating element, and the spacing of said surfaces being equal to the sum of the desired wear allowance and arc gap of said contacts plus the thickness of said operating element.

3. In a pressure responsive electrical control device, a single means affording said device a predetermined fixed operating differential and simultaneously a predetermined total contact arc gap and wear allowance, said means affording adjustability to reestablish a contact wear allowance to compensate for contact wear without affecting said operating differential and comprising integrally formed fixedly spaced surfaces limiting travel of an operating element of said device, the spacing of said surfaces being equal to the sum of the desired contact wear allowance and arc gap plus the thickness of said operating element.

4. A pressure responsive electrical control device including an operating element, and means affording said device adjustability to reestablish a desired contact wear allowance to compensate for contact wear without affecting a predetermined fixed operating differential for the device, said means comprising integrally formed fixedly spaced parallel surfaces to limit travel of said operating element and said surfaces being adjustable jointly while maintaining said fixedly spaced relation therebetween, thereby affording variation of the ratio between contact arc gap and wear allowance but maintaining the sum thereof constant.

5. A wholly enclosed pressure responsive electrical control device comprising a set of contacts, a pressure responsive operating element therefor, an enclosing casing for said device, and means affording simultaneously a predetermined total contact arc gap and wear allowance for said device and a predetermined fixed operating differential therefor, all of which may be initially set without necessity of access thereto through said enclosing casing, said means affording adjustability to reestablish a contact wear allowance to compensate for contact wear without affecting said operating differential and comprising a pair of integrally formed fixedly spaced parallel surfaces between which said operating element is adapted to oscillate, said surfaces limiting travel of said element, and the spacing of said surfaces being equal to the sum of said predetermined contact wear allowance and arc gap plus the thickness of said operating element.

6. A pressure responsive electrical control device comprising a set of contacts, a pressure responsive operating element therefor, and means affording simultaneously a predetermined fixed operating differential for said device and a contact arc gap and wear allowance, the ratio of which may be varied while the sum thereof remains constant, said means comprising fixedly spaced surfaces to limit travel of the said operating element, and the spacing of said surfaces

being equal to the sum of the desired wear allowance and arc gap of said contacts, plus the thickness of said operating element.

7. A pressure responsive electrical control device comprising, a contact biased for movement to a first position, an operating element for said contact having connection therewith to move said contact to a second position, and to release said contact for movement to said first position, and means affording simultaneously a predetermined fixed operating differential for said device and a contact arc gap and wear allowance, the ratio of which may be varied while the sum thereof remains constant, said means comprising fixedly spaced surfaces to limit travel of said operating element, and the spacing of said surfaces being equal to the sum of the desired wear allowance and arc gap of said contacts, plus the thickness of said operating element.

8. A pressure responsive electrical control device comprising, snap acting mechanism including a pressure responsive operating element and a snap acting element operated thereby, a contact connected for operation by said snap acting

element and movable relative thereto, and means affording simultaneously a predetermined fixed operating differential for said device and a contact arc gap and wear allowance, the ratio of which may be varied while the sum thereof remains constant, said means comprising fixedly spaced surfaces to limit travel of said snap acting element, and the spacing of said surfaces being equal to the sum of the desired wear allowance and arc gap of said contact plus the thickness of said snap acting element.
